INTERFERENCE REDUCING RADIO
RECEIVING SYSTEM

Louis Cohen, Washington, D. C.; Louise Sissman, administratrix of the estate of said Louis Cohen, deceased, assignor to Louise Sissman as trustee for Louise Sissman, Louis P. Sissman, Joan Louise Sissman, and Peter Louis Sissman

Application July 29, 1948, Serial No. 41,205

14 Claims. (Cl. 250—20)

1

This invention relates to the art of radio signaling and has for its object the elimination or substantial reduction of foreign electrical disturbances, including those caused by atmospheric discharges, in the reception of radio signals.

Another object of the invention is to provide a simple device which can be used with most radio receivers to eliminate or substantially reduce the effect of foreign electrical disturbances in the reception of radio signals.

Further objects of the invention are in part obvious and in part will appear from the detailed description hereinafter.

The present invention makes use of a wave conductor such as disclosed in Patent 2,415,810 issued to applicant on February 18, 1947, or in applicant's application 769,216, filed August 18, 1947, which matured into Patent 2,553,339 on June 26, 1951, but embodies the same in a simpler circuit than there disclosed.

A "wave conductor" is a conductor having such distributed inductance and capacity that its electrical length is a substantial fraction of the wave length of the desired signal, thereby permitting a substantial wave development thereon.

A convenient form of wave conductor as described in said Patent 2,415,810 is a solenoidal coil wound with a sufficient number of turns of wire, and with its distributed capacity increased by a metal plate adjustably located in proximity thereto. Although the patent discloses a flat plate, the plate may obviously be shaped to conform closely to the shape of the solenoidal coil. Numerous mechanical devices may be used to provide an adjustment of the distributive capacity by varying the separation of plate and coil. Instead of using a metal plate, the solenoidal coil may be enclosed in a metal cylinder, and the distributed capacity varied by moving the coil in or out of the cylinder. Preferably, the cylinder should be split so as not to produce the effect of a shorted turn. Instead of a solenoidal form of coil, a conically shaped coil may be employed with a conically shaped metal cap conforming closely to the exterior of the coil and capable of being displaced relative thereto along the axis of the cone or any other convenient form of plate and coil may be employed which permits ready variation of the distributed capacity between them.

Or the coil may be wound in the form of a flat spiral and associated with a flat circular metal plate adjustably positionable with respect thereto, as by hinging the flat coil and plate together at the periphery.

In addition to or in place of the adjustment in

the distributed capacity, the electrical length of the wave conductor may be varied by varying the amount of inductance included in the circuit. Thus, instead of using a simple inductance, a number of separate inductances may be employed, together with a switching arrangement which will connect a desired number of inductances in series in the circuit, or the coil may be tapped and an appropriate switch employed to connect a greater or lesser part of the coil into the circuit. Or the inductance may be separated into two portions whose mutual inductance may be varied, thus varying the total self-inductance of the system.

15 The amount of wire used may be reduced by employing powdered iron cores or other forms of iron cores with low hysteresis losses such as employed in the well-known permeability tuning arrangements. By varying the position of the core, the inductance may be tuned in the same manner as is usual with permeability tuners.

Without limiting the invention to any particular theory of operation, it is believed that basically the operation of the present invention as well as those described in said Patent 2,415,810 and application 769,216 may be explained in the manner set forth below. The circuit of the invention has been analyzed mathematically and the theory set forth here is based on such analysis. Without burdening the specification with the details of such mathematical analysis, the basic principles appear to be these:

35 When an electrical disturbance acts as an oscillatory circuit, for example, a wave conductor and its associated circuits, it sets up oscillations of a frequency determined by the parameters of the circuit system. The phase and amplitude of the current produced depends on the applied voltage, its manner of application, and the parameters of the circuit system and may be represented by the formula

$$I = E \psi (f)$$

45 where E is the applied voltage and $\psi (f)$ is a function of the frequency as determined by the circuit parameters. If the disturbing energy is applied distributively to the wave conductor, for example, if the conductor itself is made sufficiently large to serve as an energy collector, or, if the energy is applied through a distributed capacity to the wave conductor, it is possible by suitable adjustment of the circuit parameters and the amounts of energy so applied to generate a current $E_1 \psi_1 (f)$ which is equal in amplitude and opposite in phase to a current $E_2 \psi_2 (f)$ produced

by applying the same disturbance at a point on the wave conductor.

It is possible by appropriate adjustment to obtain this condition where $E_1\psi_1(f) = -E_2\psi_2(f)$ for a value of f which is different from the signal frequency, and thus balance out the effect of interfering impulses without balancing out the desired signal.

The present invention provides a simple and newer means of applying this theory to existing radio receiving sets without any modification of their structure.

In the drawings which set forth typical diagrammatic circuit systems embodying the present invention:

Fig. 1 is a diagrammatic representation of a simple form of my invention.

Fig. 2 is a modification embodying a separate control of energy transfer from a supplemental antenna.

Fig. 3 is a detail modification of the separate control of Fig. 2.

Fig. 4 is a further modification of the control.

Fig. 5 is a modification employing permeability tuning.

Fig. 6 is a modification using a single antenna.

Fig. 7 is a further modification using a single antenna.

Fig. 8 is a modification using capacitative instead of direct connection to the wave conductor.

Fig. 9 is a further modification of the device of Fig. 8.

In Fig. 1, 1 represents a simple antenna or energy collector; 2 is a wave coil or wave conductor; 3 is a metal plate adjustably positionable with respect thereto to vary the distributed capacity of coil 2 and thereby vary its effective electrical length; 4 is the antenna terminal of a radio receiver; 5 is a second antenna or energy collector which may be used to obtain improved results. The wave conductor 2 and the associated plate 3 may be of the type shown in said Patent 2,415,810, though any of the other modifications discussed above may be used instead. When the inductance 2 is connected in series between the antenna 1 and the antenna terminal 4 of any standard receiver I have found that substantial reduction in the effects of interfering electrical impulses is obtained simply by adjusting the distance separation of plate 3 from coil 2. In many cases the coil 2 and plate 3 pick up sufficient interfering energy so that no additional antenna is needed to make possible substantial balancing out of interfering signals. Generally, however, better results are obtained if a second antenna 5 is connected to the metal plate 3. The antenna 5 is generally comparable in length to antenna 1, but the relationship is not critical.

The adjustment of plate 3, it is to be observed, varies both the effective length of the wave conductor 2 as well as the effective energy transfer from antenna 5 to the oscillatory circuit via the distributed capacity between plate 3 and coil 2. Though the energy transfer and the effective electrical length are parameters which may be varied individually to obtain a condition where

$$E_1\psi_1(f) + E_2\psi_2(f) = 0$$

their joint variation by movement of plate 3 is very effective to produce a condition where substantially all noise is eliminated.

In some cases, especially where the whole device is shielded so that the tuning plate 3 does not serve as a pickup, it may be desired to tune the coil separately from the antenna coupling.

In that case it is especially desirable to provide means for varying the energy supplied by the 2nd antenna. Such an arrangement is shown in Fig. 2 where in addition to the variably positionable plate 3 for tuning the coil, a second plate 6 is provided in fixed capacitative relation to coil 2 for coupling antenna 5, the whole device being encased in grounded metal case 8. The amount of energy transferred is effectively controlled by varying condenser 7 thus by-passing more or less energy to ground.

Fig. 3 shows a modification where a variable high resistance 9 is substituted for the capacity 7 to regulate the by-pass from antenna 5 to ground.

Fig. 4 shows a further modification wherein the variable capacity 7 is placed in series with antenna 5 and plate 6, but this is not as effective as the other arrangements.

It is understood, of course, that the various means for controlling the energy transfer shown in Figures 2, 3, and 4 may also be employed where the antenna 5 couples directly to the tuning plate 3 as in Fig. 1, and thus make it possible to more closely control the balance than is possible in Fig. 1 where the energy transfer from antenna 5 is controlled solely by tuning plate 3.

Fig. 5 is a further modification showing the use of permeability tuning. Coil 2 is tuned by insertion or withdrawal of the low-hysteresis iron core 10. The second antenna 5 is coupled to coil 2 by plate 6 fixed in capacitative relation thereto. Energy transfer from antenna 5 is regulated by variable capacity 7 controlling the amount of bypass to ground. In place of capacity 7, a variable resister may be used as shown in Fig. 3, or the arrangement of Fig. 4 may be employed.

Fig. 6 is a modification using a single antenna which is applied directly to the end of coil 2 and also through the plate 3. The variable condenser 11 serves to control distribution of energy between the two paths. A second variable condenser 12 may optionally be employed in the other branch of the antenna lead.

A similar result is obtained in Fig. 7 where the antenna 1 is connected to the rotor 13 of a condenser having a split stator comprising a half 14 connected to plate 3 and a half 15 connected to coil 2. Changing the position of the rotor varies the distribution of energy between coil 2 and plate 3.

Although in most of the previous figures the coil 2 has been shown as connected directly in series in the lead from antenna 1, this coupling may be made capacitative as shown in Fig. 8. 16 and 17 are metal strips in capacitative relation to coil 2 and adjustable both along the length thereof and with respect to their separation therefrom thereby making possible a variation in the length of coil included in the antenna circuit and the amount of energy transfer. Strip 16 connects to antenna 1 and strip 17 to antenna terminal 4 of a radio receiver.

Figure 9 is a modification of the device shown in Fig. 8 which is useful with receivers having a primary serial coil coupled to a tuned input circuit. In this modification, R is a radio receiver having an aerial coil 19 connecting to antenna terminal 4 and in inductive relation to secondary 20 which forms a tuned circuit with condenser 21. Terminals 22 and 23 connect to the grid and filament respectively of a detecting or amplifying tube. Antenna 1 connects to coupling strip 16 and antenna terminal 4 to coupling strip 17, exactly as in Fig. 8. An additional coupling strip

13 connects to the grid side of the tuned input of the receiver R. This modification, by appropriate adjustment of the position of the various coupling strips, including an adjustment both as to position along the length of the coil and distance separation therefrom of strip 16 gives very good results without the use of the second antenna 5, which, however, may also be used in this modification.

While the invention has been described as embodied in specific forms for purposes of illustration, it should be understood that the invention is not limited thereto, since various modifications will suggest themselves to those skilled in the art without departing from the spirit of the invention, the scope of which is set forth in the annexed claims.

I claim:

1. A device for reducing the effect of interfering energy associated with desired signal energy in a radio receiving system comprising a radio receiver connected to an antenna solely through the intermediary of a wave conductor comprising said wave conductor, means for connecting one point on said wave conductor to an antenna, means for connecting another point on said wave conductor to the antenna terminal of a radio receiver, an energy collector, distributive capacity coupling means for applying mixed signal and interfering energy from said energy collector to said wave conductor, and means for varying the electrical length of the wave conductor to reduce the effect of said interfering energy on the reception of the desired signal.

2. A device as in claim 1 including means for varying the relative amounts of interfering energy transferred to the wave conductor directly from the antenna and through the distributed capacity coupling means.

3. A device as in claim 2 including means for by-passing to ground a desired proportion of the energy applied to the distributed capacity coupling means.

4. A device as in claim 3, wherein the amount of energy by-passed to ground is varied by means of a variable capacity in the by-pass lead to the ground.

5. A device as in claim 3, wherein the amount of energy by-passed to ground is varied by means of a variable resistor in the by-pass lead to the ground.

6. A device as in claim 2 including a variable capacity connected between the distributive capacity coupling means and a means for connection to an energy collector.

7. A device as in claim 2, wherein a metal plate adjustably positionable with respect to the wave conductor serves both to vary the energy transferred through the distributive capacity coupling means and to vary the effective electrical length of the wave conductor.

8. A device as in claim 2, wherein the electrical length of the wave conductor is variable by means of permeability tuning, and including separate means to vary the amount of energy transferred to the wave conductor through the distributive capacity coupling means.

9. A device as in claim 1 including means for varying the electrical length of the wave conductor and means for varying the relative amounts of energy applied to the wave conductor distributively and at a point.

10. An antenna system for reducing the effect of interfering energy comprising an antenna, a wave conductor connected at one point to the antenna, means for connecting a second point on the wave conductor to the aerial terminal of a radio receiving system, a second antenna, adjustable distributive capacity coupling means for applying the energy from the second antenna to the wave conductor, and means for varying the effective electrical length of the wave conductor.

11. In a radio receiving system comprising a radio receiver connected to an antenna through the intermediary of a wave conductor and having a tuned input circuit and an antenna coil inductively coupled thereto, a wave conductor, a metal plate adjustably positionable with respect to the wave conductor and an energy collector connected thereto, an antenna capacitatively coupled to one point on the wave conductor, means to capacitatively couple another point on the wave conductor to one terminal of said antenna coil, and means for capacitatively coupling a third point on the wave conductor to said tuned input circuit.

12. In a radio receiving system, a wave conductor, an antenna directly connected to one end of said wave conductor, the other end of said wave conductor being directly connected to the aerial terminal of a radio receiver, a metal plate adjustably positionable with respect to the wave conductor to substantially reduce the effect of interfering energy on the reception of desired signals, and an energy collecting means connected to said plate.

13. A device as in claim 12 in which the energy collector is connected to a metal plate in fixed capacitative relation to the wave conductor, the wave conductor and associated plates are enclosed in a grounded metal container, and means to regulate the amount of energy transfer from said energy collector to the wave conductor.

14. A device as in claim 12 in which the metal plate is adjustably positionable with respect to the wave conductor in such manner as to vary both the total amount of coupling between the plate and the wave conductor and the relative amount of coupling between the plate and different points along the wave conductor.
